UNITED STATES PATENT OFFICE.

AXEL O. APPELBERG, OF SCHENECTADY, NEW YORK, ASSIGNOR TO GENERAL ELECTRIC COMPANY, A CORPORATION OF NEW YORK.

VACUUM RESISTANCE-FURNACE.

953,774.

Specification of Letters Patent. Patented Apr. 5, 1910.

Application filed July 2, 1906. Serial No. 324,391.

To all whom it may concern:

Be it known that I, AXEL O. APPELBERG, a subject of the King of Sweden, residing at Schenectady, county of Schenectady, State 5 of New York, have invented certain new and useful Improvements in Vacuum Resistance-Furnaces, of which the following is a specification.

This invention relates to an improvement 10 in electric furnaces and particularly to means whereby a temperature may be produced approaching that at which some of the so-called high fusing metals disintegrate or vaporize.

15 The furnace may be used for the fusion or treatment of the more refractory metals and compounds, and includes means for protecting the charge under treatment from oxidation or other change which might result 20 from contact with air or other atmosphere at the high temperature of treatment.

25 My improved furnace is of the resistance type and is provided with a resistance conductor consisting of substantially pure metal and operative at an exceedingly high temperature. I have hereinafter described the resistance conductors as composed of tungsten, as I consider that metal typical of the general class of refractory metals which may 30 be used to advantage in the furnace hereinafter described.

The details of my invention are illustrated in the drawings forming a part of this specification, in which—

35 Figure 1 is a perspective view of one type of furnace with certain of the parts shown in section; Fig. 2 is a plan view taken on the line 1—1 of Fig. 1; Fig. 3 is a representation of the crucible to be heated and of the 40 resistance conductors and the surrounding refractory shield; Fig. 4 is a detail illustrating the connection between a resistance conductor and the metal block by which it is supported; and Fig. 5 is a sectional elevation 45 of a modified type of furnace in which the resistance heater is tubular in form.

The furnace shown in Fig. 1 comprises an air tight metal chamber 1 fitted with a cover 2 through which extends a metal tube 3 50 whereby the chamber may be connected with a vacuum pump and may be exhausted and maintained in an exhausted condition throughout the operation of the furnace. A brass tube 4 passes down through the

cover to near the bottom of the chamber and 55 is then bent in a circular form and passes upward and out again through the cover. This tube is insulated from the cover and serves to connect the resistance members of the furnace with one side of an electrical circuit. 60 A similar tube 5 is arranged in circular form near the top of the evacuated chamber to support the upper ends of the heating members. These heating members 6 consist of metal rods produced as herein- 65 after described, and clamped at their ends in blocks 7 of the same material, the latter being secured to iron clamps 8 by suitable clips. The clamps 8 are mounted on the brass tubes 4 and 5 and are insulated there- 70 from by mica bushings 9, with the exception of the clamps 10 and 11 which connect with the end conductors of the group; these are mounted directly on the brass rods and thereby establish a connection for current 75 from the source of power through the group of rods in series. They may conveniently be made of copper.

When the heating conductors are made of tungsten they may be pressed to the desired 80 form from finely powdered tungsten, but for convenience in manufacture it is sometimes desirable to add a small quantity of binding material to the tungsten powder and then squirt or mold the mixture into 85 rods and blocks necessary for the construction of the furnace. A 50% glucose solution is a suitable binder and may be added to the tungsten powder in the proportion of about 5 parts by weight. When glucose is 90 used I prefer to add to the mixture about 10% of tungstic oxid so that when the mixture is heated up in the furnace there may be enough oxygen present to eliminate all carbon and yield a refractory body of pure 95 tungsten. This mixture when first molded or pressed is rather brittle and inclined to crumble but I find that by heating it in a vacuum to about 1300° C., I can completely change its characteristics and render it 100 strong and relatively tough. After this treatment it can be machined and otherwise manipulated much like artificial graphite. Before the furnace is put into regular operation I consider it advisable to heat these 105 tungsten parts to a temperature considerably higher than 1300° C. in order to drive out all vaporizable components such as unre-

duced tungstic oxid, but this treatment can be conveniently carried out in the furnace itself after the latter has been assembled.

For simplicity in the drawings I have omitted from Fig. 1 the crucible and its support, and I have shown in dotted lines the location of a refractory screen consisting of a plurality of superimposed rings 12 of tungsten. These parts are shown in Fig. 3 disposed in proper relation to the refractory heaters 6. The rings 12 constitute a shield to prevent dissipation of heat toward the metal walls of the chamber and to reflect radiant heat on the crucible located within the heating space. The rings 12 may be conveniently insulated from other parts of the apparatus by non-conductive and refractory bushings 13. The crucible 14 containing the charge to be melted may be supported on a tungsten pedestal 15 carrying a cap 16. The pedestal 15 may be conveniently supported by iron bars 17 engaging with the lower brass pipe 4 and insulated therefrom.

The brass pipes 4 and 5 serve not only to transmit current to and from the refractory conductors but they also serve as means for carrying a cooling liquid through blocks 8, 10, and 11 whereby these parts are maintained at a relatively low temperature even though the resistance conductors are run at an exceedingly high heat.

To insure a good connection between the refractory heaters 6 and the blocks 7 in which they are mounted, I may use the means of connection shown in Fig. 4. The lower block is provided with a cup 18 filled with tungsten powder in which the lower end of the refractory heater is embedded. The powder is pressed firmly in position by means of a tungsten bushing 19 pushed down on top of the powder. I find that such a joint becomes very strong after the initial operation of the furnace, because of sintering or similar action between the particles of the powder whereby the entire joint becomes relatively solid and strong and insures a good electrical connection to the refractory heater. At the top of the heater the joint is similarly made except that the heater enters the cup of tungsten powder from below. As an alternative means of connecting the heaters I may clamp the ends between tungsten blocks.

The furnace may be water cooled and may be provided with a suitable peep hole 21 covered with a plate of mica 22.

The modification shown in Fig. 5 includes many of the features shown in Fig. 1, but is provided with a tubular heater in place of the series of rods heretofore described. This tubular heater 23 is clamped at the top in a tungsten block 24 and the latter is electrically connected to a U-shaped tube 25 of brass or other metal. At the bot-

tom the refractory tube is mounted in a 65 tungsten cup 26 and the latter is clamped between suitable tungsten blocks 27, one of which is shown in the drawings. A second metal tube 28 serves as a means for connecting the lower end of the heater with the 70 electrical circuit and also serves to support the annular shield 29 which surrounds the heating tube and concentrates the heat within the tube. A tungsten pedestal 30 is mounted within the tube to serve as a support 75 for a crucible or other article to be heated. I prefer to insulate this pedestal from other parts of the heater by a lava bushing 31 and I prefer to insulate the tungsten shield from the supporting clamps 80 32 by similar bushings 33 to decrease the tendency for dissociation of the heater or of the heated parts because of the liberation of charged particles at the enormous temperature to which these elements are subjected 85 during normal operation of the furnace. If desired, the tubular heater may be divided by a helical slot to increase the voltage across the heater for any given current.

I find either of the modifications above 90 described to be very serviceable for the treatment of the more refractory metals and materials and for the production of a predetermined and controllable temperature. The furnace may be used for the continued 95 heating of tungsten without danger of contaminating the charge by vapors or charged particles given off by the heating elements of the furnace. As the entire evacuated chamber is free from carbon, the highest 100 temperature may be produced without danger of contaminating the charge with carbon, or producing a carbid from the material under treatment.

What I claim as new and desire to secure 105 by Letters Patent of the United States, is,—

1. The combination of an air-tight chamber, a tungsten heater therein, and a crucible supported in said chamber in proximity to said heater.

2. In a vacuum furnace, a tungsten screen inclosing a heating space, a tungsten conductor within said space, means for exhausting air from said space, and means for supporting a material to be heated in proximity to said heater.

3. The combination of an air-tight chamber, means for continuously exhausting air from said chamber, and a refractory heating member mounted in said chamber and consisting of compressed tungsten powder.

4. In a vacuum furnace, a heating member consisting of compressed tungsten powder, means for supporting material to be heated in proximity to said heating member, and terminals for the heating member consisting of tungsten blocks.

5. In a vacuum furnace, a heating space

- having tungsten walls, and a refractory heater therein of substantially pure tungsten.
6. The combination of an air tight chamber, means for supporting material to be treated in said chamber, and means out of contact with said material for heating it to a temperature approaching the fusing point of tungsten, in a space free from carbon.
- 10 7. In a vacuum furnace, a resistance conductor of compressed tungsten powder, and material to be treated placed in proximity to said heater and receiving radiant energy therefrom.
- 15 8. A vacuum furnace of the resistance type having an incandescent conductor of substantially pure tungsten.
9. A vacuum furnace of the resistance type having an incandescent conductor consisting substantially of pure metal powder sintered into a coherent body and having a fusing temperature as high or higher than the temperature at which carbon appears to disintegrate.
- 20 10. The combination of an air-tight chamber, means for supporting a charge of metallic material therein, and a resistance conductor for heating said charge said conductor consisting of material the vapor of which is chemically inert with respect to the charge under treatment at temperatures approaching the fusing temperature of the more refractory metals.
11. A furnace of the resistance type having a furnace chamber inclosing a tubular 35 resistance conductor of substantially pure tungsten.
12. A vacuum furnace of the resistance type having a furnace chamber inclosing a tubular resistance conductor of substantially pure tungsten within which the material to be heated can be introduced.
13. The combination of an evacuated chamber, a tungsten tube therein, means for supplying current to said tube to heat the 40 same, and means for supporting material within said tube but out of contact therewith.
14. A tubular resistance member of pure tungsten having a bore large enough to admit a crucible.
15. A tubular resistance heater of pure tungsten having a helical slot.
- In witness whereof, I have hereunto set my hand this 30th day of June, 1906.
- AXEL O. APPELBERG.
